UNITED STATES PATENT OFFICE.

FRED L. MANNY, OF BENTON HARBOR, MICHIGAN, ASSIGNOR TO BAKER-VAWTER COMPANY, OF BENTON HARBOR, MICHIGAN, A CORPORATION OF MICHIGAN.

BINDER.

1,354,205.

Specification of Letters Patent. Patented Sept. 28, 1920.

Application filed September 11, 1917. Serial No. 190,743.

To all whom it may concern:

Be it known that I, FRED L. MANNY, a citizen of the United States, residing at Benton Harbor, in the county of Berrien and State of Michigan, have invented certain new and useful Improvements in Binders, of which the following is a specification.

My invention relates to binders intended to contain bodies of detached leaves, and commonly known as loose-leaf binders. The object of my invention generally is the provision of improved mechanism permitting the body of sheets to be quickly and securely clamped together, and as quickly released from clamped engagement when it is desired to withdraw or insert any sheets, the operating mechanism being mounted in a novel binder frame designed and constructed to operate with such mechanism. In carrying out my invention I have made provision for the actuation of the clamping mechanism through the turning of a key-operated member, and the release thereof through a reverse turning of the key, and have provided a locking bar arranged to automatically lock when inserted in the binder and be released by means of the key, as hereinafter more fully described. My invention consists in various novel combinations of parts and groups of associated members in the binder structure herein described, the essential elements of which are more particularly pointed out in the appended claims.

In the drawings Figure 1 is a central longitudinal section—on the line 1—1 of Fig. 2—through the back of the binder, the side cover, partly shown in elevation being broken away; Fig. 2 is an inside face view or plan view of the back of the binder, a portion of the cover plate being broken away to show parts of the mechanism below; Fig. 3 is a perspective of the frame members at one corner of the binder; Fig. 4 is a side elevation of one end of the binder, looking in the same direction as in Fig. 1; Figs. 5, 6, 7 and 8 are cross-sections of the back of the binder, on the lines 5—5, 6—6, 7—7 and 8—8, respectively, of Fig. 2; Fig. 9 is a detail showing a locking lever adjacent one side of the binder; and Fig. 10 is a small detail showing the bit of the key by means of which the binder is adjusted and unlocked.

The same reference characters indicate the same parts in all the figures of the drawings.

The binder structure may be said generally to consist of back frame plate 1, in which are slidably mounted two spring-pressed side frame plates 2 having side portions 2^b carrying hinged covers 3, which side frame plates, by suitable equalizing mechanism, have an equal sliding movement in opposite directions upon the back plate to adjust the distance between them as desired. The side plates are equipped with telescoping binder posts, as hereinafter more fully described, and a removable extensible locking post is also provided.

As shown in Figs. 1 and 3, the ends 1^a of the back plate 1 are bent up at right angles, and the edges 1^b of the ends bent inwardly and downwardly to form a groove to embrace guide bars 4 of the irregular form shown in Fig. 3 secured to and structurally forming a part of the opposite side plates 2. These side plates each consist of a portion 2^a parallel with the back plate and which will be termed the horizontal portion, and a portion 2^b lying at a right angle thereto and which will be termed the vertical portion. In the rectangular recesses between the side portions of the side frame plates and the guide bars are secured cushion blocks 5 by means of short headed studs 6 formed with internally threaded sockets engaged by headed screws 7. These screws also serve as a means for securing two post bars 8 respectively to the opposite side plates 2, such bars being further supported near the center of each by a pair of studs 9—9 secured to the side plates and having threaded sockets engaged by headed screws 10. The upper edges of the post bars are recurved and lie against the top flanges 2^c which extend inwardly from the opposite vertical portions 2^b of the side plates 2 between the cushion blocks 5.

The back frame plate 1, adjacent each end and centrally thereof has secured to it a stud 11 which is formed with an internally threaded socket adapted to receive a screw 12 by means of which a cover plate 13 is rigidly secured to the back. This plate is further supported by other studs also secured to the back plate and forming pivots for certain mechanism to be later described. Each end of the cover plate, between the

stud 11 and the guide strip 4 of the side plate 2 has secured to it a pair of depending metal straps 14, one at each edge of the plate, which support a pair of tubes 15, one 5 end of each tube being closed and the opposite end open, and the open ends being at opposite sides of the cover plate. Inner tubes 16 are arranged to telescope within the tubes 15 and within each pair of associated tubes 15 and 16 is arranged a strong spring 17 which with the springs in the other tubes tends at all times to yieldingly urge the side plates 2 and connected parts away from each other. To each side plate 2 and its associated post bar 8 is secured one member each of four extensible, telescoping binder posts consisting each of an inner tube 18 and outer tube 19. In the present instance, for convenience in assembling the parts, the 10 tubes 18 and 19 are not secured to either the side plate or post bar, but are flanged at their bases to coöperate with short sleeves 20 extending between and abutting against the side plate and its associated post bar. 15 The sides 21 of the binder are hingedly supported upon hinge plates 22 secured to the side plate members 2^b of the frame,—see Figs. 1, 3 and 4.

The clamping and equalizing mechanism 20 by which the sides 2 are compelled to move equally and uniformly together and apart and by which they are clamped against a body of interposed sheets in the binder will now be described.

Secured to the back plate 1 and arranged along a median line passing through the posts 11 are four other posts 23, 24, 25 and 26, all formed with threaded sockets for the reception of screws by which the cover plate 25 is rigidly secured to the back plate. To one side plate 2 is secured a couple of cross racks 27—27, one near each end, and the other side plate a similar couple of cross racks 28—28. On the stud 23 near one end 30 of the binder is pivotally mounted a double pinion 29, the lower gear of which lies between the adjacent racks 27 and 28, and on the stud 26 near the opposite end of the binder is mounted a similar pinion 30 arranged in like manner between the other racks 27 and 28. Slidingly mounted on the under side of the cover plate 13 are two longitudinal rack bars 31 and 32 formed toward their ends with rack teeth on their adjacent edges meshing with the upper gears of the pinions 29 and 30. These rack bars are slidingly secured to the cover plate by means of underhanging retaining brackets 33 secured to such plate and lugs 34 struck down from such plate. The adjacent edges 35 of the central portions of the rack bars 31 and 32 are also formed with teeth which mesh with a gear wheel 35 which is rotatably mounted in a manner which will shortly be explained concentrically of the

post or stud 25. It is obvious that the positive gear connection between the gear wheel 35 and the cross racks 27 and 28 will compel an equal and uniform movement of the two side frame plates 2 and connected parts in 70 opposite directions, that is, either toward or away from each other, the springs 17 at all times urging the sides to spread position.

The train of gearing by which the wheel 35 is rotated to open and close the sides of 75 the binder frame includes a pinion 36 having a short hub journaled in the adjacent vertical side plate member 2^b and confined between such plate and a bearing plate 37 secured to the horizontal portion 2^a of the 80 side plate. This hub is recessed to receive a suitable turning key, the bit 38 of which is shown in Fig. 10. The pinion 36 meshes with a pinion 38^a secured to a worm 39 which adjacent said last-mentioned pinion is 85 journaled in the side frame member 2^b and which is also confined under a curved tongue 37^a forming part of the bearing plate 37. The worm 39 meshes with a worm gear 40 secured to a hub pivotally mounted on the 90 post 24, to which hub is also fixed a pinion 41 meshing with a pinion 42 secured to a hub which is pivotally mounted on the post 25. The upper face of this hub is formed with ratchet teeth 42^a arranged to 95 coöperate with ratchet teeth 35^a on the under side of the pinion or gear wheel 35 before mentioned. Between the cover plate 13 and the top of the worm gear 40 is arranged a retaining plate 43, one end of which curves 100 downwardly around the worm 39, and the other end of which overlies a release bar hereinafter described. The upper end of the post 25 is of reduced diameter, forming a shoulder which restrains the pinion 35 and ratchet from downward movement. The pinion 42 is relatively thin, as compared with the pinion 41, and its hub has sufficient play to permit disengagement of the ratchet teeth 42^a while the pinions 41 and 42 remain in mesh. A coiled expansion spring 105 44 arranged in a cylindrical bore formed in the hub of the pinion 42 serves to yieldingly hold the ratchet teeth 42^a in engagement with the ratchet teeth 35^a.

For the purpose of forcing the pinion 42 downwardly to release the ratchet connection 42^a—35^a, a release bar 45 is provided, consisting of a mutilated rod having a flat side arranged adjacent the upper face of 110 said pinion. In a longitudinal bore formed in one end of this rod—the end adjacent the pinion 36—is seated a screw pressed plunger 46 to which is fixed a disk 47 formed with ratchet teeth 47^a and also with a stop lug 47^b 115 arranged to coöperate with a stop lug 45^a on the bar 45. The ratchet teeth 47^a are adapted to coöperate with ratchet teeth 48 formed on the hub of a pinion 49 which is in mesh with the pinion 36 before mentioned. 130

On its inner side the hub of the pinion 49 is formed with a socket pivotally supporting the outer end of the plunger 46, which extends beyond the disk 47.

5 In addition to the telescoping posts 18-19 secured to the post bars 8 of the frame, I have provided an extensible removable locking post, shown in Figs. 7 and 8. This post consists of a tube 50 in which is arranged to 0 slide a headed rod 51 pressed by a spring 52 toward extended position. The outer end of the tube 50 is provided with a head 53 formed with an annular locking groove, and with a key socket arranged to receive the 5 bit 38 of the operating key before mentioned. This binder post is inserted in registering holes in the side frame members 2^b and post bars 8, and when inserted is retained in place by means of a spring pressed 20 locking pawl 54 which is pivoted upon a stud 55 secured to the side frame member 2^b and which engages the locking groove in the head 53 of the post. The pawl is cammed aside by the inclined front end of the tube 25 50 as the post is inserted, and released by inserting and turning the key, the prongs of the bit of the key forcing the pawl out of the locking groove.

30 The binder posts 18-19, it may be here explained, are intended to engage open notches, or slots in the edges of the sheets which are used in the binder, while the removable post 50 is designed to engage holes or perforations in the sheets for the purpose 35 of preventing removal by anyone not provided with a key.

30 The operation of the binder will readily be understood from the foregoing description without detailed explanation. Assuming the binder to be open and the locking post removed and that it is desired to place a body of sheets in the binder and close and lock it, the sheets will be inserted upon the binder posts and the sides pressed together 40 against the pressure of the springs 17 to grasp the sheets as tightly as convenient. The equalizing racks will force the sides to come together equally in perfect parallelism, and the ratchet 35^a-42^a will permit the 45 pinion 35 to rotate without moving the pinion 42. The key is now applied to rotate the pinion 36 in a righthand direction, and through the pinion 38, worm 39, worm gear 40, and pinions 41, 42 and 35, and connected 50 racks mechanism, the sides may be clamped together as tightly as desired, the pitch of the worm and proportions of the pinions and gears being such as to avoid any interference 55 or locking up as the sides shift their position relatively to the back plate.

60 In thus turning the key the pinion 36 will rotate the pinion 49 and ratchet 48-47^a until the stop lug 47^b comes into contact with the lug 45^a on the release bar 45, after which 65 the teeth 48 will cam the teeth 47^a and plun-

ger back without moving the release bar, the plunger spring being weaker than the spring 44 in the hub of the pinion 42.

The removable locking post may now be inserted and pushed in until it automatically 70 locks through engagement of the pawl 54 in the locking groove of the post, after which the leaves cannot be removed or the sides unclamped by anyone who is not provided 75 with a key.

When it is desired to open the binder and remove the sheets, the locking post is first removed, and the key then applied to the key socket of the pinion 36 and turned in the reverse direction, which will first rotate 80 the pinion 49 and ratchet members 48-47^a until the lug 47^b has made nearly a complete revolution and come into contact with the other side of the lug 45^a,—the pinion 38 and its connections meanwhile slackening 85 the sides somewhat,—after which a further turning movement of the key will turn or twist the release bar 45, and its flat face will cam the pinion 42 downwardly against the tension of its spring 44, thus releasing the 90 clutched engagement of the ratchet members 42^a-35^a. This will permit the springs 17 to exert their stress and the sides of the binder 95 will open apart.

I claim:

1. In a loose-leaf binder, a back plate, side plates slidably mounted therein, cross racks secured to said side plates, a longitudinal rack slidably mounted on said back plate, pinions intermediate said longitudinal rack 100 and cross racks, another pinion geared to said longitudinal rack, a ratchet coupling one member of which is connected to said last mentioned pinion, and manually operable means coöperating with the other member of said coupling for clamping the side plate against interposed sheets.

2. In a loose-leaf binder, a back plate, side plates slidably mounted therein, spring tension means yieldingly tending to spread 110 said side plates apart, cross racks secured to said side plates, a longitudinal rack slidably mounted on said back plate, pinions intermediate said longitudinal rack and cross racks, another pinion geared to said longitudinal rack, a ratchet coupling one member of which is connected to said last mentioned pinion, and a manually operable train of gearing including a worm and co-operating worm gear coöperating with the 115 other member of said coupling for clamping the side plates against interposed sheets.

3. In a loose-leaf binder, a back plate, side plates slidably mounted therein, cross racks secured to said side plates, a longitudinal rack slidably mounted on said back plate, pinions intermediate said longitudinal rack and cross racks, another pinion geared to said longitudinal rack, a ratchet coupling 125 one member of which is connected to said 130

last mentioned pinion, manually operable means coöperating with the other member of said coupling for clamping the side plates against interposed sheets, and means for dis-
5 connecting said ratchet coupling.

4. In a loose-leaf binder, a back plate, side plates slidably mounted therein, spring tension means yieldingly tending to spread said side plates apart, cross racks secured to said side plates, a longitudinal rack slidably mounted on said back plate, pinions intermediate said longitudinal rack and cross racks, another pinion geared to said longitudinal rack, a ratchet coupling one member 10 of which is connected to said last mentioned pinion, a manually operable train of gearing including a worm and coöperating worm gear coöperating with the other member of 15 said coupling for clamping the side plates against interposed sheets, and means for disconnecting said ratchet coupling.

5. In a loose-leaf binder, a back plate, side plates slidingly mounted therein, cross racks secured to said side plates, equalizing gearing co-operatively connected with said cross racks, spring tension means yieldingly tending to spread said side plates apart, and a train of gearing co-operatively connected with said sides and including a key-operated member arranged to draw said sides together when turned in one direction, and disconnecting means operated by said key-operated member when turned in the opposite direction for disconnecting said train of gearing.

6. In a loose-leaf binder, a back plate, side plates slidingly mounted therein, cross racks secured to said side plates, equalizing gearing co-operatively connected with said cross racks, a pinion connected to said equalizing gearing, a coupling one member of which is fixed to said pinion and the other member of which is normally spring-pressed into co-operative relation with said first-mentioned member, and a key-operated member arranged when turned in one direction to rotate the coupled members of said coupling and when turned in the other direction to shift the second-mentioned member thereof out of co-operative relation with the first-mentioned member.

7. In a loose-leaf binder including a back plate, a pair of side plates slidably mounted therein, mechanism for shifting said side plates comprising a rotatable operating member, connections intermediate said member and side plates including a ratchet coupling, and separate connections co-operating with one member of said ratchet coupling for disconnecting said first-mentioned connections.

8. In a loose-leaf binder including a back plate, a pair of side plates slidably mounted therein, mechanism for shifting said side plates comprising a rotatable operating

member, connections intermediate said member and side plates including a ratchet coupling, and separate connections intermediate said operating member and one member of said ratchet coupling for disconnecting said first-mentioned connections.

9. In a loose-leaf binder, mechanism according to claim 8 in which the separate connections between the operating member and ratchet coupling member includes a second ratchet coupling.

10. In a loose-leaf binder, mechanism according to claim 8 in which the separate connections between the operating member and ratchet coupling member includes a second ratchet coupling, one of the members of said ratchet coupling being operatively connected with a cam and said cam being operatively connected with said ratchet coupling member to shift it to uncoupled position. 8

11. In a loose-leaf binder including a back plate, a pair of side plates slidably mounted therein, mechanism for shifting said side plates comprising equalizing gearing cooperatively connected with said side plates, a pinion arranged to actuate said equalizing gearing, a key-operated pinion, a worm geared to said pinion, a train of gearing intermediate said worm and first-mentioned pinion and including a ratchet coupling, and separate connections intermediate said key-operated pinion and one member of said ratchet coupling including a second ratchet coupling, said key-operated pinion operating when turned in one direction to draw the sides together and when turned in the other direction to shift said member of the first-mentioned ratchet coupling to uncoupled position

12. In a loose-leaf binder, a back plate, side plates slidably mounted therein, cross racks secured to said side plates, a longitudinal rack slidably mounted on said back plate, pinions mounted on said back plates intermediate said longitudinal rack and cross racks, another pinion mounted on said back plate geared to said longitudinal rack, and mechanism connected with said last mentioned pinion for adjusting the spread of the side plates comprising a worm transversely mounted on one side plate, means for operating said worm, a worm gear mounted on said back plate, and gearing intermediate said worm gear and last mentioned pinion. 120

13. In a loose-leaf binder, a back plate having vertical end portions turned over at the top to form guide flanges, side plates having horizontal portions parallel and adjacent said back plate and vertical portions equipped with hinged covers, said side plates being equipped with guide plates slidingly engaging under the guide flanges of the end portions of the back plate, coiled expansion 130

springs arranged between the side plates at its opposite ends, a cover plate spaced apart from said back plate and secured thereto, and operating mechanism arranged between 5 said cover plate and said back plate for drawing the sides toward each other.

14. A loose-leaf binder according to claim 13 having post bars secured to the side plates above the plane of the cover plate, and 10 freely telescoping binder posts secured between said side plates and post bars.

15. In a loose-leaf binder, a back plate having vertical end portions turned over at the top to form guide flanges, side plates having horizontal portions parallel and adjacent said back plate and vertical portions equipped with hinged covers, guide plates having an attaching portion secured to said side plates and a slide portion at

right angles thereto slidingly engaging under 20 the guide flanges of the end portions of the back plate, said guide plates being offset adjacent the ends of the sides between their attaching portion and slide portion, and cushion blocks in the space between the side 25 plates and the guide plates.

16. In a loose-leaf binder having extensible side frame plates formed with vertical flanges, post bars secured to said plates and arranged to embrace a body of interposed 30 sheets, a telescoping expandible locking post adapted to be inserted through registering orifices in the flange of the frame plate and post bar on one side, and locking mechanism 35 coöperating with the head of said locking post arranged between such frame plate and post bar.

FRED L. MANNY.
